BUNTING DEVICE

James J. Clark, Bronx, N. Y.

Application October 21, 1946, Serial No. 704,703

5 Claims. (Cl. 273—89)

1

This invention relates to new and useful improvements in a baseball game device.

This application relates to similar subject matter to that in my U. S. Letters Patent No. 2,362,188, issued on November 7, 1944.

The invention proposes to characterize the bunting device by the fact that it includes a bat rotatively mounted on a vertical post to swing horizontally and resiliently urged in one direction with a coil spring mounted coaxially on the post. A catch is associated with the bat for holding the coil spring in a wound condition with the bat set for batting. It is proposed to provide one or more levers associated with and for operating mechanism to free the bat by operating the catch. An important feature of this invention resides in the provision of certain mechanism for holding an elastic stretched in the path of motion of the bat for cushioning or dampening the swing of the bat for bunting when this is desired.

Still further the invention proposes the construction of a baseball bunting device embodying the objects and advantages briefly described, which is exceptionally simple and which may be manufactured and sold at a low cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary plan view of a portion of a baseball game provided with a baseball bunting device constructed in accordance with this invention.

Fig. 2 is an elevational view of one of the handle operators.

Fig. 3 is a fragmentary perspective view of the bunting device shown in Fig. 1.

Fig. 4 is a fragmentary enlarged sectional view taken on the line 4—4 of Fig. 3.

The baseball bunting device, in accordance with this invention, includes a base 10. A vertical post 11 is mounted on the base 10. A bat 12 is rotatively mounted on the vertical post 11 and is adapted to swing horizontally. A coil spring 14 is coaxially mounted on the vertical post 11 and has one end attached to the bat 12 and the other end attached to the post 11. This coil spring 14 is for the purpose of swinging the bat 12. It is merely necessary to turn the bat 12 around and around until the spring 14 is sufficiently wound. When the bat is released, the

2

spring 14 will swing it horizontally. The bat is located in the corner of the supporting base 10. The major part of the mechanism for releasing the bat is under the top surface of the base so as not to interfere with the batting of the ball.

A catch 15 is mounted on the base 10 and is located in the path of the bat 12 for holding the bat stationary, and set for batting with the coil spring 14 fully wound up. This catch 15 is in the nature of a leaf spring which has an end 16 attached upon the base 10 and which extends upwards and laterally and then continues into a downwardly directed end portion 17. The bat 12 has a flat side 18 adapted to engage against the downwardly bent end 17 of the catch 15.

The catch 15 is associated with means by which it may be operated to release the bat 12. This means includes a rod 20 turnably mounted upon the base 10 with several brackets or bearings 21.

20 The rod 20 is provided with a bent inwardly projecting portion 22 terminating beneath the downwardly bent end 17 of the catch 15.

The projecting portion 22 is connected with the inwardly bent portion 17 with a rod or cable 23.

25 Each end of the rod 20 is provided with a handle 24 by which the rod 20 may be turned. Springs 25 are interposed between the bottom faces of the handles 24 and a bracket 26 on the base 10 and act to normally urge the handles 24 into slightly raised positions.

30 When one or the other of the handles 24 are pressed downwards the rod 20 will turn and the projection 22 will move downwards, indirectly flexing the catch 15 for moving the catch beneath the bat 12 which is then freed. A stop 27 mounted on the base 10 limits the swing of the bat 12.

A hollow rod 28 is turnably mounted on the base 10 by several brackets or bearings 29. The hollow rod 28 is provided with an upwardly directed back end 30. A bell crank having arms 31 and 32 is pivotally mounted intermediate of its arms upon said back end 30 of said hollow rod 28 by a pintle 33.

45 A rod 34 is movably mounted through the hollow rod 28 and is connected with the bell crank 31 and 32 for controlling the pivotal position thereof. The back end of the rod 34 is provided with an upwardly directed and flattened end 36 which has a slot 37 engaged by a pin 38 mounted on the arm 32 of the bell crank 31 and 32. The hollow rod 28 has an upwardly directed handle 39 by which it may be easily moved forwardly and rearwardly and turned. The rod 34 has a handle 40 by which it may be moved and turned. 50 55 The hollow rod 28 is also provided with a lateral

projection 41 which limits turning of the rod 28 in one direction because the projection 41 strikes the top face of the base 10. An elastic 43 is stretched between a loop member 44 mounted on the base 10 and the outer end of the arm 31 of the bell crank. The tension of the elastic 43 normally holds the bell crank arm 31 and back end 36 directed upwardly because the elastic 43 is past the dead center of pivoting of the rod 28, causing the projection 41 to engage the face of the base 10.

The operation of the baseball bunting device may be understood from the following:

The bunting device is ready to be used when it is in the position illustrated in Fig. 3 of the drawing. When a ball is pitched towards the bat 12, the player may depress one of the handles 24 to operate the catch 15 to free the bat 12 at the proper instant so that the bat swings and strikes the ball. The inner end of the bat 12 will strike the elastic 43 which is in its path. The elastic 43 will serve to dampen the swing of the bat. The tension of the elastic 43 may be varied for controlling the type of bunt. The rod 34 may be moved inwards or outwards relative to the rod 28 so as to indirectly pivot the bell crank 31 and 32 and stretch or relax the elastic 43. Friction will retain the rod 34 in its adjusted position within the hollow rod 28.

When it is desired not to use the bunting device the rods 28 and 34 may be turned so that the elastic 43 and the back end 30 and back end 36 of the rods 28 and 34, respectively, lay against the top face of the base 10, as schematically indicated by the dot and dash lines in Fig. 3 of the drawing. The stop 27 prevents the bat 12 from turning around too much so that the spring 14 would unwind. The stop 27 limits the bat 12 to turn through approximately 180°.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A baseball bunting device, comprising a base, a vertical post mounted on said base, a bat rotatively mounted on said vertical post to swing horizontally, a coil spring mounted on said post and having one end attached to said bat for swinging said bat, a catch mounted on said base and located in the path of said bat for holding said coil spring wound up, means for moving said catch free of said bat, a hollow rod turnably mounted on said base and having an upwardly directed back end, a bell crank pivotally mounted on the back end of said hollow rod, an elastic stretched between said base and one end of said bell crank and normally disposed in the path of said bat for dampening swinging of said bat, and a rod movably mounted through said hollow rod and connected with said bell crank for controlling the amount to which said elastic is stretched.

2. A baseball bunting device, comprising a base, a vertical post mounted on said base, a bat rotatively mounted on said vertical post to swing horizontally, a coil spring mounted on said post and having one end attached to said bat for swinging said bat, a catch mounted on said base and located in the path of said bat for holding said coil spring wound up, means for moving said

catch free of said bat, a hollow rod turnably mounted on said base and having an upwardly directed back end, a bell crank pivotally mounted on the back end of said hollow rod, an elastic stretched between said base and one end of said bell crank and normally disposed in the path of said bat for dampening swinging of said bat, and a rod movably mounted through said hollow rod and connected with said bell crank for controlling the amount to which said elastic is stretched, said hollow rod being provided with a projection for limiting turning in one direction to a position in which said elastic is slightly past the dead center of said hollow rod.

15 3. A baseball bunting device, comprising a base, a vertical post mounted on said base, a bat
rotatively mounted on said vertical post to swing
horizontally, a coil spring mounted on said post
and having one end attached to said bat for
swinging said bat, a catch mounted on said base
and located in the path of said bat for holding
said coil spring wound up, means for moving said
catch free of said bat, a hollow rod turnably
mounted on said base and having an upwardly
directed back end, a bell crank pivotally mounted
on the back end of said hollow rod, an elastic
stretched between said base and one end of said
bell crank and normally disposed in the path of
said bat for dampening swinging of said bat, and
0 a rod movably mounted through said hollow rod
and connected with said bell crank for controlling
the amount to which said elastic is stretched, said
hollow rod and said rod being provided with
handles.

4. A baseball bunting device, comprising a base, a vertical post mounted on said base, a bat rotatively mounted on said vertical post to swing horizontally, a coil spring mounted on said post and having one end attached to said bat for

40 swinging said bat; a catch mounted on said base and located in the path of said bat for holding said coil spring wound up, means for moving said catch free of said bat, a hollow rod turnably mounted on said base and having an upwardly directed back end, a bell crank pivotally mounted on the back end of said hollow rod, an elastic stretched between said base and one end of said bell crank and normally disposed in the path of said bat for dampening swinging of said bat, and a rod movably mounted through said hollow rod and connected with said bell crank for controlling the amount to which said elastic is stretched, said rod being slidable through said hollow rod.

5. A baseball bunting device, comprising a base, a vertical post mounted on said base, a bat rotatively mounted on said vertical post to swing horizontally, a coil spring mounted on said post and having one end attached to said bat for swinging said bat, a catch mounted on said base and located in the path of said bat for holding said coil spring wound up, means for moving said catch free of said bat, a hollow rod turnably mounted on said base and having an upwardly directed back end, a bell crank pivotally mounted on the back end of said hollow rod, an elastic stretched between said base and one end of said bell crank and normally disposed in the path of said bat for dampening swinging of said bat, and a rod movably mounted through said hollow rod and connected with said bell crank for controlling the amount to which said elastic is stretched, said rod having a back end provided with a slot, and a pin mounted on one arm of said bell crank and slidably engaging said slot.
